UNITED STATES PATENT OFFICE.

JEAN THEOBALD, OF MERIDEN, CONNECTICUT, ASSIGNOR TO INTERNATIONAL SILVER COMPANY, OF MERIDEN, CONNECTICUT, A CORPORATION OF NEW JERSEY.

DESIGN FOR A TABLE SET.

Application filed June 29, 1928. Serial No. 27,321. Term of patent 7 years.

To all whom it may concern:

Be it known that I, JEAN THEOBALD, a citizen of the United States, residing at Meriden, county of New Haven, and State of Connecticut, have invented a new, original, and ornamental Design for a Table Set, of which the following is a specification, reference being had to the accompanying drawing, forming a part thereof.

The drawing is a perspective view of a table set showing my new design.

I claim:

The ornamental design for a table set as shown.

JEAN THEOBALD.
